UNITED STATES PATENT OFFICE.

JAMES O. STEWART, OF ALAMEDA, CALIFORNIA.

RAKING APPARATUS FOR ORE-ROASTING FURNACES.

SPECIFICATION forming part of Letters Patent No. 236,274, dated January 4, 1881.

Application filed December 18, 1879.

To all whom it may concern:

Be it known that I, JAMES O. STEWART, of Alameda, county of Alameda, State of California, have invented certain new and useful 5 Improvements in Raking Apparatus for Ore-Roasting Furnaces; and I do hereby declare that the following is a full, clear, and exact description thereof, reference being had to the accompanying drawings.

10 My invention contemplates improvements in raking apparatus for ore-furnaces; and it consists of rakes having tubular handles and tubular and perforated heads, an upright tube having valves adapted to be acted on by tubular cross-bars of the rakes, a flexible hose or air-tube, and a blower, combined with an ore-furnace, substantially as hereinafter more fully set forth.

Referring to the accompanying drawings, 20 Figure 1 is a side elevation with a part of the outer wall removed. Fig. 2 is an end view taken from the left-hand side of Fig. 1, with the outer wall broken away. Fig. 3 is a detail view of the rectangular hearth-tubes. 25 Figs. 4 and 5 are detail views of the rakes. Fig. 6 is a vertical transverse section through line x x , Fig. 2.

A represents the body of the furnace, which is built square or rectangular and of the desired height, and is provided with a feed-hopper, B, on its top. Inside of this furnace I place one or more tubular hearths, C, at the desired distance above each other, as shown. 35 Each floor is made of a number of square tubes, C' C', which are placed close together, so as to form a continuous surface or floor, while each tube serves as a conductor of heat, as hereinafter described. The furnace is built with a double wall on two of its sides, and the 40 two walls on each side are far enough apart to form narrow side chambers between them. The hollow tubes, which form the floors of the furnace, pass through the inner walls, E, and are supported by them, while the outer walls, 45 F, are solid. The space between these two walls I also divide up, as hereinafter described.

Instead of building a single fire-place entirely across one side of the furnace, I employ two fire-places, G G', one on each side of the 50 furnace. The fire-place on one side extends from the front to near the middle of the fur-

nace, while the fire-place on the opposite side extends from near the middle of the furnace to its rear side, as shown. I then divide the spaces between the double side walls into two 55 separate chambers by means of upright partitions H, so as to compel the heat from each fire-place to pass upward through the tubes on its own half of the furnace. These side spaces I again divide by horizontal partitions I, so 60 as to compel the heat and products of combustion to pass back and forth through the tubes in alternate directions until they reach the upper series of tubes, where the upright partition H terminates, so as to allow the heat 65 and products of combustion from both fire-places to mingle and pass through the upper set of tubes to the chimney or stack J. This gives a uniform heat throughout the furnace and prevents the products of combustion coming in contact with the ore. The ore, as it 70 passes through the hopper B, falls upon the upper floor, and is stirred and moved by the rake, hereinafter described, until it falls through an opening, d, at the rear of the floor 75 upon the next lower floor. Here the next rake takes it in a like manner, and rakes and moves it along over the floor to the front side of the furnace, where it falls through an opening upon the next lower floor, and so on down 80 from one floor to the other, being raked and stirred on each floor in the same manner until it is finally discharged at the bottom.

Working-doors are made at the front of the furnace opening into each ore-chamber. Sliding doors are also placed over the opening in each furnace-hearth, through which the ore is discharged from hearth to hearth and to the receptacle beneath, so that either can be closed, 85 as desired, in order to retain the ore a longer 90 or shorter period on the hearth.

The ore-chambers between the tubular floors are each connected with a chimney or stack, K, on one side of the furnace, into and through which the gases generated by the heat in the 95 roasting-chambers are drawn off, thus forming a complete muffle-furnace.

My mechanical stirring apparatus consists of a frame-work constructed at the rear of the furnace. This frame has two or more horizontal guide-rails, L L, on each side, opposite each other, between which cross-heads M are ar-

ranged to slide. The cross-heads are connected together by an upright frame-work, N, and the entire frame-work and cross-heads are moved back and forth toward and from the furnace by a crank, O, which is driven by suitable power. The rake-heads *e* and their handles *f* are tubular, ordinary gas-pipe serving for the handles, and the handles pass through the upright sliding frame N, and are secured to it by set-screws *b*, so that when the rake-heads are placed in the ore-chambers and their handles extend out horizontally and are attached to the sliding frame the rakes will be caused to move simultaneously back and forth over all the floors when the sliding frame is moved. The rakes are represented in the present instance with two handles, and the outer ends of these handles are connected by a tubular cross-bar, *s*, which projects to one side, as shown.

P is a vertical tube, which is attached to the sliding frame, so as to move with it, and its upper end is connected with a blower, Q, by a flexible hose, R. The tube P has a number of valves, *t*, occupying coincident positions with and adapted to be held open by projecting portions of the rake cross-bars *s*. To hold the valves *t* open, the cross-bars of the rakes are adjusted and secured by means of the set-screws *b* against and so as to press the said valves inwardly. The rake-heads, as stated, are also tubular, so that when the rakes are fixed in their raking position air will be forced by the blower through the flexible tube R, vertical tube P, cross-bar *s*, tubular handles *f*, into the tubular rake-heads, and thence, through minute holes or perforations in the under side of the rake-head, into and upon the ore while it is being stirred.

Should it be desired to put out of operation any one or more of the rakes, it is only necessary to loosen its set-screws and move it by its handles until the cross-bar of the handles is sufficiently removed from the carrying-frame as to prevent contact therewith as the frame travels back and forth with and is operating the other rakes. The valve *t* is then closed, after which the remaining rakes can be operated in the same manner as above described. The air is thus delivered through the rake-head so as to impinge directly into and upon the ore in finely-divided streams as the rakes stir it up and turn it over, so that every particle of ore is thoroughly oxidized. The air passing through the handles keeps them cool,

and at the same time the air is partially heated 55 before it strikes the ore, so that the temperature of the furnace is not interfered with.

This stirring apparatus and blower can be used in any furnace having one or more flat hearths—such as the ordinary reverberatory 60 furnace—and by properly shaping the rake-teeth they can be made to stir the ore, and also to move it forward continuously to the discharge-openings, stirring and discharging at the same time. 65

A modification of my furnace is applied when it is desired to allow the products of combustion from the fire-place to mingle with the gases from the ore-chamber. In this case I use only one fire-place, extending entirely across 70 one side of the furnace, and instead of making the hearths or floors of tubes, I leave the ends of the tubes, where they rest in the wall, tubular; but I cut away the under side of the tubes between the ends, so that the products of combustion and gases can mingle. This form of hearth-tubes I call "open-bottom tubes." 75

I am aware that it is old to construct a furnace with end flues and alternate series of tubular hearths and ore-chambers, and with fire-boxes located diagonally opposite to each other, the products of combustion of which are confined to their respective halves or sides of the furnace and caused to pass tortuously through the tubes or hearths to and through a 85 common tube.

I am further aware that it is old to rake or stir the contents of a furnace and to pass simultaneously into said contents air or a blast through the rake. 90

Having thus described my invention, what I claim, and desire to secure by Letters Patent, is—

The raking apparatus constructed of the rakes *e*, *f*, having tubular handles and tubular and perforated heads, the upright tube P, having valve *t*, acted upon by tubular cross-bars *s* of the rakes, the flexible tube or hose R, and the blower Q, in combination with the furnace A, substantially as and for the purpose set 100 forth.

In witness whereof I have hereunto set my hand and seal.

JAMES O. STEWART. [L. S.]
